United States Patent

Des. 238,376

Patented Jan. 6, 1976

238,376

ELECTRONIC CALCULATOR

Lewis H. Herr, Lansdale, Paul W. Porter, Norristown, and John S. Kovacs, East Norriton, Pa., assignors to Sperry Univac Division, Sperry Rand Corporation, Blue Bell, Pa.

Filed Aug. 26, 1974, Ser. No. 500,402

Term of patent 7 years

Int. Cl. D18—01
U.S. Cl. D26—5 C

FIG. 1

FIG. 2

FIG. 3

FIG. 4

FIG. 5

FIG. 6

FIG. 1 is a top plan view of an electronic calculator showing our new design;

FIG. 2 is a right side elevational view thereof;

FIG. 3 is a front elevational view thereof;

FIG. 4 is a bottom plan view thereof;

FIG. 5 is a left side elevational view thereof; and

FIG. 6 is a rear elevational view thereof.

What we claim is:

The ornamental design for an electric calculator, substantially as shown and described.
